UNITED STATES PATENT OFFICE.

RICHARD B. ISEMAN, OF CLARION, PENNSYLVANIA.

AUTOMOBILE-TURNTABLE.

1,380,385.

Specification of Letters Patent.

Patented June 7, 1921.

Application filed October 15, 1920. Serial No. 417,074.

To all whom it may concern:

Be it known that I, RICHARD B. ISEMAN, a citizen of the United States, residing at Clarion, in the county of Clarion and State of Pennsylvania, have invented certain new and useful Improvements in Automobile-Turntables, of which the following is a specification.

My invention relates to automobile turntables of the traveling type, and particularly to devices of this type which comprise a base member having mobility wheels, and a turret mounted to rotate on the base and provided with means for supporting an automobile.

One object of my invention is a novel construction of the base and turret to permit of ready access to the bearings and at the same time to prevent tilting of the turret with respect to the base.

I will describe one form of turn table embodying my invention, and will then point out the novel features thereof in claims.

25 In the accompanying drawings, Figure 1 is a top plan view of a turn table embodying my invention. Fig. 2 is a side elevation of the turn table shown in Fig. 1. Fig. 3 is a plan view of one half of the base and 30 turret, a portion of the turret being broken away to expose part of the base to view. Fig. 4 is a transverse vertical section of the turn table on the line IV—IV of Fig. 3, looking in the direction indicated by the 35 arrows.

Similar reference characters refer to similar parts in each of the several views.

Referring now to the drawings, the turn table comprises a base 10, which in general 40 is shaped like a ring, but which is provided with four offset portions 10^a in each of which is journaled a mobility wheel 11. These wheels project a slight distance below the under surface of the base, and as 45 is well understood, they are adapted to effect the mobility of the turn table as a whole along a suitable track, or, if desired, along a plane surface, such as the floor of a garage.

The upper surface of the base 10 is provided with a horizontal and circular track or race 12, which serves to support the turret as I will explain hereinafter. The turret, which is designated as a whole by the 50 reference character 13, is ring-shaped and comprises a horizontally disposed portion 13^a located directly above the track 12, and a

vertically disposed flange 13^b. The flange 13^b projects downwardly and is of such size as to fit within the main portion of the base 10 with ample clearance to insure freedom of rotation of the turret with respect to the base. The horizontal portion 13^a is provided with a plurality of rectangular apertures 15 in each of which is journaled a roller 14. These rollers project below the under surface of the horizontal portion 13^a, and are arranged to ride on the track 12, thereby providing for support of the turret on the base and at the same time permitting the turret to revolve on the base with minimum friction.

Journalized at intervals in the vertically disposed flange 13^b are a series of beveled rollers 16 which are arranged to coact with a beveled track 17, which is provided on the inner surface of the base 10. Each roller 16, it will be observed, is mounted to rotate on a horizontal axis. These rollers serve to keep the turret properly centered with respect to the base, and they also serve to prevent tilting of the turret with respect to the base, both functions being accomplished with minimum friction and so with practically no resistance to the rotation of the turret on the base.

As here shown, the upper surface of the base 10 is provided with an upstanding circular flange 10^a at the outer edge of the track 12, which flange serves to keep foreign matter away from the track 12 and the rollers 14.

Attached to the turret 13 are two automobile carriers 18, 18, each of which, as here shown, is in the form of an angle bar comprising two horizontal members 18^a and 18^b connected by a vertical web 18^c. The horizontal member 18^a rests on the top of the turret 13 and is attached thereto by bolts, while the horizontal member 18^b lies close to the floor and constitutes a support for the wheel of an automobile. The two carriers 18 are disposed on opposite sides of the turret, and are parallel as shown in Fig. 1. The spacing of these carriers and the length of the same are such as to accommodate the four wheels of an automobile.

To provide the proper rigidity, the two carriers are preferably connected by two channel bars 19, 19 adjacent to the turret, and by two angle bars 20, 20 at the opposite ends of the structure.

The manner in which turn tables of the type described are used in garages and other

automobile repositories is so well understood that no further explanation is required herein. I desire to point out, however, that the device which I have described is simple 5 in construction, and that it provides for access to the operating parts without disturbing any part of the structure.

Although I have herein shown and describe only one form of turn table embodying 10 my invention, it is understood that various changes and modifications may be made therein within the scope of the appended claims without departing from the spirit and scope of my invention.

15 Having thus described my invention, what I claim is:

1. A traveling automobile turn table comprising a base provided with mobility wheels and having a vertical circular aperture, a 20 turret located above said base and having a circular depending flange passing through the aperture in said base, rollers located between said base and said turret, other rollers carried by said flange and co-acting with 25 said base, and automobile carriers supported by said turret.

2. A traveling automobile turn table comprising a ring-shaped base provided with mobility wheels, a ring-shaped turret having 30 a flange projecting downwardly into said base, rollers located between said base and said turret for revolubly supporting the turret on the base, and other rollers located between said base and said turret for preventing 35 tilting of the turret with respect to said base.

3. A traveling automobile turn table com-

prising a ring-shaped base provided with mobility wheels, a ring-shaped turret having 40 a flange projecting downwardly into said base, rollers located between said base and said turret for revolubly supporting the turret on the base, and other rollers located between said base and said turret for centering the turret with respect to the base. 45

4. A traveling automobile turn table comprising a ring-shaped base provided with mobility wheels, a ring-shaped turret having 50 a flange projecting downwardly into said base, rollers located between said base and said turret for revolubly supporting the turret on the base, and other rollers located between said base and said turret for preventing tilting of the turret with respect to the base and centering the turret with respect to 55 the base.

5. A traveling automobile turn table comprising a ring-shaped base provided with mobility wheels, a ring-shaped turret having 60 a flange projecting downwardly into said base, rollers located between said base and said turret for revolubly supporting the turret on the base, and beveled rollers mounted on horizontal axes in said flange and coöperating with a beveled track on said base. 65

6. A traveling automobile turn table comprising telescoping base and turret members, rollers interposed between said members for revolubly mounting the turret on the base, and other rollers interposed between 70 said members for centering the turret with respect to the base.

In testimony whereof I affix my signature.
RICHARD B. ISEMAN.
